Primary Examiner — Robin V Webster*Assistant Examiner* — James C Thorn, Sr.(74) *Attorney, Agent, or Firm* — Hamre, Schumann, Mueller & Larson, P.C.(57) **CLAIM**

The ornamental design for a H-type pant, as shown and described.

DESCRIPTION

FIG. 1 is a front view of an H-type pant.

FIG. 2 is a back view of the H-type pant depicted in FIG. 1. FIG. 3 is left side view of the H-type pant depicted in FIG. 1; and,

FIG. 4 is a top view of the H-type pant depicted in FIG. 1. The broken lines shown in the drawings represent heat seal or glue lines in the non-woven fabric.
